UNITED STATES PATENT OFFICE.

WILLIAM H. JOHNSON, OF DELHI, NEW YORK, ASSIGNOR OF ONE-HALF TO
JOHN McMURRAY, OF SAME PLACE.

HARNESS-RING WITH SHIELD OR RIDER.

SPECIFICATION forming part of Letters Patent No. 392,272, dated November 6, 1883.

Application filed August 31, 1882. Serial No. 284,235. (No model.)

To all whom it may concern:

Be it known that I, WILLIAM H. JOHNSON, a citizen of the United States, residing at Delhi, in the county of Delaware and State of New York, have invented certain new and useful Improvements in Harness-Rings with Shields or Riders; and I do hereby declare the following to be a full, clear, and exact description of the invention, such as will enable others skilled in the art to which it appertains to make and use the same.

My invention is designed for protecting leather straps of harness against abrasion or undue wear from contact with the metal rings which are used as connections between certain main parts of the harness and said straps. It is especially useful on neck-yoke, breeching, bit, and hame strap rings, which, from their constant riding motions and wearing actions, soon destroy the straps connected to them; and the object of my improvement is to afford a protection to these straps against the destructive and rapid wear resulting from such motions of the said rings; and to this end my invention consists in providing the aforesaid and other adaptable rings of harness with clasping sliding shields or riders interposed between the straps and inner circular surfaces of the rings, said shields or riders being formed with lateral jaws or horns, forming guides for the straps, and also causing the shields or riders to slide back and forth, and thus accommodate themselves to the circular oscillatory movements of the straps, and during said movements the rings bearing all the wearing action which comes between them and the riders, and thereby saving the straps from the destructive effect of such action, and at the same time the connecting ends of the straps are free to oscillate without injurious friction at right angles to the movements of the riders, as will be hereinafter described.

In the accompanying drawings, Figure 1 is an elevation of my invention as applied to ride on a neck-yoke, the holdback-strap to which it is attached being shown in section and the neck-yoke in end view. Fig. 2 is a transverse section in the line xx of Fig. 1. Fig. 3 is a detail section in the line yy of Fig. 1. Fig. 4 is another mode of constructing my invention, this being especially adapted for

breeching, hame, and bit rings; and Fig. 5 is a transverse section in the line zz of Fig. 4. Fig. 6 is a perspective view of my invention on harness as in use on a horse.

55

The letter A in the drawings represents one of the harness-rings riding on the yoke of a carriage-pole. This ring is provided on its inner surface with a concentrically-movable metal sliding shield or rider, B, of segmental or sector form in a longitudinal direction and of about semicircular form in transverse direction, and this rider is constructed with circular clamping-lugs b and inwardly-extended jaws b', forming a guide for the strap C, to which the ring is attached, said jaws being a proper distance from the ends of the rider, as shown. For smaller rings, as shown in Figs. 4 and 5, and on the hame and bit strap rings in Fig. 6, the inner side of the rider may be used as the seat or base for the strap C, as will be presently described; but for neck-yokes I preferably construct the rider with a roller, D, hung between the jaws b' b', upon which roller the strap bears without being bent out of its original transverse shape, and with which it will oscillate on the ring without injurious wearing friction, while the rider B is also oscillated by the strap to any position on the ring without friction between the ring and strap, the movements mentioned being at right angles to one another.

When used in smaller rings, the rider B may be provided with only one pair of clamping-lugs located at about its center, as shown in Fig. 4. These lugs b are made parallel before the rider is put upon the ring, so that they can be easily slipped over the ring and closed or shut while cold, and for the same reason the middle portion of the rider is formed at first with parallel sides, which, when the rider is to be attached to a ring, can be hammered or otherwise bent while cold around the ring, so as to make a snug but loose fit upon the same. After this the strap is attached in the usual way between the jaws or horns of the rider, being passed through the ring, as shown. It will be seen that the two pairs of clamping-lugs b in Fig. 1 are arranged at the ends of the rider. This is done to prevent the rider from being twisted upon the ring, and thus becoming liable to be caught or jammed, and at

95

100

the same time save metal, secure lightness, and avoid unnecessary frictional contact. In rings of smaller size it will be sufficient for this purpose to give the body portion of the rider a sufficient amount of girt or saddle shape, as shown, at the two ends, because the circular clamping-lugs at the center will prevent it from being accidentally separated from the ring.

10 The within-described invention, although suited and intended for the special rings above enumerated and illustrated, will, as is obvious, answer for other rings used on harness, and wherever used it serves when the connected parts are subjected to unequal or periodical strains, or, in other words, are frequently taut and loose in turns, for reducing wear and tear of such straps.

15 What I claim is--

1. The combination, with a harness-ring, of 20 a metal rider, B, formed concentric with the ring, applied on the inside of the ring, and having circular clamping-lugs *b* and angular jaws *b'*, forming a strap-guide, substantially as and for the purpose described.

25

2. The combination, with a harness-ring, of a metal rider, B, provided with clamping-lugs and angular jaws *b'*, and fitted loosely around said ring on its inside, and an anti-friction roller, D, substantially as and for the purpose 30 described.

In testimony whereof I hereunto affix my signature in presence of two witnesses.

WILLIAM H. JOHNSON.
